UNITED STATES PATENT OFFICE.

THOMAS A. EDISON, OF WEST ORANGE, NEW JERSEY, ASSIGNOR TO THOMAS A. EDISON,
INCORPORATED, OF WEST ORANGE, NEW JERSEY, A CORPORATION OF NEW JERSEY.

STORAGE BATTERY.

Original No. 1,596,826, dated February 17, 1925, Serial No. 698,633, filed March 12, 1924. Application for
reissue filed February 3, 1926. Serial No. 85,806.

My invention relates to storage batteries and more particularly to storage battery cells having the same general characteristics as the cell disclosed in Patent No. 1,377,194, granted to me on May 10, 1921. Although designed especially for use in connection with Edison storage battery cells wherein nickel hydroxide is opposed to finely divided electrolytically active iron or oxide of iron in an alkaline solution as the electrolyte, it is to be distinctly understood that my invention is not limited in its application to cells of this type.

In the cell disclosed in the patent referred to, a battery pile of special construction is employed in the place of the usual plate assembly in Edison storage battery cells. This battery pile comprises a series of very thin conductive contact sheets, preferably of nickel, separated by insulating sheets of asbestos paper, with thin flat layers of finely divided active material respectively disposed between the surfaces of each of the nickel sheets and the adjacent asbestos sheets, the whole being held together under great pressure with the layers of active material in firm, close surface contact with the respective nickel sheets. The layers of active material for the negative elements, preferably consist of electrolytically finely divided iron or oxide of iron, preferably mixed with a small amount of mercury, and the layers of active material for the positive elements preferably consist of finely divided nickel hydroxide. Other suitable active materials may, however, be employed instead of the finely divided iron and nickel hydroxide; for example, in place of finely divided iron as the active material for the negative elements, finely divided cadmium or cobalt may be employed; and in place of nickel hydroxide as the active material for the positive elements, an oxide of cobalt may be employed.

In making up a battery pile such as that described above, I have heretofore proceeded as follows: The asbestos insulating sheets used in the battery pile were first coated on one side with a thin layer of finely divided iron or oxide of iron, and on the other side with a thin layer of nickel hydroxide. These coated asbestos sheets were then subjected to enormous pressure so as to compact the layers of active material and

form the same with very smooth flat surfaces. The proper number of coated asbestos sheets were then superimposed with one of the thin nickel contact sheets between each two adjacent asbestos sheets in such a manner that one of each two adjacent nickel sheets was engaged on each side with a layer of the electrolytically active iron or oxide of iron and the other was engaged on each side with a layer of the electrolytically active nickel hydroxide, so as to form a pile with electrode elements which were alternately negative and positive. This superimposed pile was then subjected to great pressure and secured together under pressure by means of heavy clamping or pressure plates at either end of the pile and two bolts or rods extending through the clamping plates and also through the elements of the pile and nuts threaded on said rods. These rods served as the poles of the battery pile, for one of said rods contacted only the contact sheets of the negative electrode elements of the pile and the other of said rods contacted only the contact sheets of the positive electrode elements of the pile. This was accomplished by providing the contact sheet of each electrode element with two openings through which the said rods respectively extended, the opening for one rod being of such size that the rod fitted very closely therein, and the opening for the other rod being of somewhat greater size so that the rod which extended therethrough was spaced from the wall of such opening.

I find, however, that cells constructed as above described become unduly heated both on charge and discharge, that the capacity of such cells, especially at high discharge rates, is considerably below that which should be obtained, and that the capacity decreases to some extent with the length of time the cells are in use. I believe these conditions to be correctly explained as follows: In cells so constructed the surface contact of the nickel conductive sheets and the layers of active material engaging the same is so close and said layers of active material are so compacted because of the great pressure to which said layers were subjected in forming the battery piles, and also because of the pressure under which the piles are maintained, that it is extremely difficult for any appreciable amount of the electrolyte to gain

access to the layers of active material except such portions thereof as are directly exposed to or closely adjacent the body of the electrolyte in the cells. Moreover, the internal resistance and heating of such cells, both on charge and discharge, are materially increased by osmotic action. This action takes place in the direction of the flow of current and when the cells are on charge has the effect of driving the small amount of electrolyte which might otherwise reach those portions of the layers of active material of the positive electrode elements which are remote from the body of the electrolyte, away from the adjacent surface portions of the nickel contact sheets of such elements, while when the cells are discharged it has the effect of driving the electrolyte which might otherwise reach the corresponding portions of the layers of active material of the negative elements, away from the adjacent surface portions of the nickel contact sheets of these elements. When the electrolyte is thus driven away from the nickel contact sheets of the electrode elements, the adjacent active material is rendered practically dry and as such material is a very poor conductor when dry, the electrical resistance thereof and the internal resistance of the cells will thereupon be greatly increased. That the foregoing explanation is correct is substantiated, in part at least, by examinations which I have made of cells of the type described after the same have been in use, which examinations show the active material adjacent the edges of the different layers thereof to be fully formed and the material remote from the edges of the said layers to be either only partially formed or in such condition that it is clear that such material was not being acted on by the electrolyte. It is therefore obvious that in such cells the circulation of the electrolyte and the access thereof to all portions of the various layers of active material were so impaired that in the operation of the cells, a large portion of the active material was inactive or only partially active.

The principal object of my invention is to obviate the foregoing objections by the provision of an improved arrangement and construction, especially in the type of cells above described, for so improving or increasing the circulation of the electrolyte as to insure a constant and copious supply of electrolyte to all portions of the active material of the electrode elements both on charge and discharge.

I have discovered that the foregoing object may be attained to a marked degree in a cell such as described, by providing an arrangement wherein the active material between each of the conductive members or sheets and the adjacent insulating members or sheets is so disposed as to facilitate the circulation of the electrolyte through such

active material and between said conductive and insulating members or sheets so that the electrolyte may readily reach all portions of the active material, and preferably an arrangement in which the active material has interrupted surface contact with the respective conductive members and means such as suitable passageways, where the surface contact is interrupted, for facilitating the circulation of the electrolyte, as for example an arrangement in which those surfaces of the layers of active material which are adjacent the nickel sheets, or other conductive contact sheets, are provided with suitably formed grooves which are properly arranged in the cell. Where circulating passageways consisting of grooves of this character are employed, such grooves are preferably formed in the active material by the use of suitably shaped dies when subjecting the asbestos sheets coated with the active material to the heavy initial pressure, prior to assembling the battery pile.

Other objects and features of my invention will be hereinafter more fully described and claimed.

In order that my invention may be more clearly understood, attention is directed to the drawing accompanying and forming a part of this specification and in which:

Figure 1 is an enlarged, fragmental sectional view of a storage battery cell of the type disclosed in my Patent No. 1,377,194, referred to above, wherein the arrangement for facilitating the circulation of the electrolyte consists in the provision of the active material with passageways in the form of grooves of the special type above referred to;

Figure 2 is a plan view of one of the coated asbestos insulating sheets of the cell shown in Figure 1 prior to the assembly hereof in the battery pile; and

Figure 3 is an enlarged sectional view of a number of the elements in the battery pile of the cell shown in Figure 1.

Referring to the drawing, reference character 1 represents the asbestos insulating and separating sheets which are disposed between the adjacent negative and positive electrode elements of the battery pile. Prior to the assembly of the pile each of a plurality of these asbestos sheets is coated on one side or face with electrolytically active finely divided iron and on the opposite side or face with finely divided nickel hydroxide. Each of the coated sheets is then subjected between a pair of dies to a pressure of several thousand pounds per square inch. When the arrangement for facilitating the circulation of the electrolyte comprises passageways in the active material in the form of grooves such as shown in the construction illustrated, the faces of these dies are preferably provided with similar series of ribs or ridges, and in using the dies the same

are arranged with the corresponding ribs or ridges thereof in alignment so that in subjecting the coated sheet to pressure therebetween, as described, substantially the entire surface portions of the active material on both sides of the sheet will have impressed or formed therein similar series of closely spaced grooves 30 of shallow depth with the corresponding grooves in the active material on opposite sides of said sheet in alignment. The grooves of each series are preferably parallel and preferably extend in the direction of the narrow dimension of the coated sheet, where the latter is rectangular in shape, as shown in Figure 2. If desired, however, additional grooves extending lengthwise of the coated sheet and intersecting the grooves shown, may be provided, and, especially where the coated sheets differ in shape from those shown, other arrangements such as passageways or grooves of various other shapes, sizes and disposition may be used. A plurality of coated asbestos sheets after being subjected to the pressure and grooved as described, together with a plurality of thin contact sheets, preferably formed of nickel, are then assembled into a battery pile A, with the corresponding grooves 30 in the various layers of active material in alignment. The battery pile A comprises a plurality of superposed and alternately arranged negative and positive electrode elements, each of the negative elements consisting of a thin contact sheet or foil 4, preferably of nickel, and two layers 5 of electrolytically active finely divided iron respectively disposed on opposite sides of the sheet or foil 4; and each of the positive elements consisting of a thin contact sheet or foil 6, similar to the sheets or foils 4 of the negative elements, and two thin layers 7 of finely divided nickel hydroxide respectively disposed on opposite sides of the sheet or foil 6 and in contact therewith. The insulating sheets of asbestos paper are respectively disposed between the negative and positive elements, each of these sheets being, of course, coated on one side with a layer 5 of finely divided iron which is in contact with the adjacent thin nickel sheet or foil 4, and on its other side with a layer 7 of nickel hydroxide which is in contact with the adjacent nickel sheet or foil 6. Strong heavy nickel-plated pressure plates are respectively disposed at the opposite ends of the superposed negative and positive elements, only one of these plates, indicated by reference character 9, being shown. The contact sheet or foil 4 of each of the outermost negative elements is not in contact at its outer surface with a layer of finely divided iron but is merely separated and insulated from the adjacent pressure plate by an uncoated insulating sheet 10. Reference character 11 represents one of the two rods or poles which extend through the elements of the battery pile and the pressure plates to hold the pile assembled. The rod or pole 11 shown is the negative pole and fits closely against the wall of the opening provided therefor in each of the contact sheets 4 of the negative electrode elements, but the opening 12 provided in each of the contact sheets 6 of the positive electrode elements for said pole 11 is of such size that the pole will be spaced from the wall of this opening as clearly shown in Figure 1. The asbestos sheets 1 and 10 and the layers of active material 5 and 7 are also provided with openings 13 and 14 through which the poles extend and which are of such size that the poles will not contact the walls of these openings. The openings in the contact sheets 6 for the positive pole, not shown, will, of course, be of such size that the positive pole will closely engage the walls of these openings, while the openings in the contact sheets 4 of the negative electrode elements provided for the reception of the positive pole will be of such size that said pole will not engage the walls thereof. Each of the rods or poles is insulated from each of the pressure plates at the end of the battery pile by a hard rubber bushing 15 and a hard rubber washer 16.

In the particular cell shown and described, the grooves 30 in the faces of the layers of active material which are adjacent the contact sheets 4 and 6 constitute passageways extending through the battery pile and located between spaced surface sections of active material having close, intimate contact with each surface or side of each contact sheet, the said passageways providing means whereby the electrolyte 3, 105 may readily circulate through the battery pile and gain access to all portions of the active material without it being necessary for the electrolyte to work its way through the active material for any great distance. 110 Therefore in the operation of the cell, there will be a sufficiently free and rapid circulation of the electrolyte to ensure a constant and copious supply thereof to all portions of the active material. Accordingly substantially all of the active material will be fully formed soon after the cell is put into operation, and thereafter practically all of such material will be active. Moreover because of the improved circulation of the 115 electrolyte, the deleterious effects of osmotic action are largely obviated and the heat generated in the battery pile is dissipated more rapidly and effectively. In a battery cell embodying the present invention, the internal resistance is reduced, the capacity, especially at high discharge rates is greater, and the cell is generally more efficient in operation.

It is to be understood that my invention is 130

not limited to the construction shown and specifically described herein, but that such construction is merely illustrative of the manner in which the active material may be disposed or arranged to facilitate the circulation of the electrolyte in cells of the type described and is subject to various changes and modifications without departure from the spirit of my invention and the scope of the appended claims.

Having now described my invention, what I claim as new and desire to protect by Letters Patent is as follows:

1. In a storage battery cell, a conductive member, an insulating member and active material held under pressure between said members and having only spaced sections of that surface thereof adjacent the conductive member, in close, intimate contact with such conductive member thereby providing passageways to facilitate the circulation of the electrolyte through the active material, substantially as described.

2. In a storage battery cell, a conductive member, an insulating member and active material held under pressure between said members, said active material having means whereby the surface contact thereof with the conductive member is interrupted for facilitating the circulation of electrolyte through the active material, substantially as described.

3. In a storage battery cell, a conductive sheet, an insulating sheet and active material held under pressure between said sheets, said active material having spaced surface sections in close, intimate contact with said conductive sheet the spaces between said surface sections facilitating the circulation of electrolyte through the active material, substantially as described.

4. In a storage battery cell, a conductive member, an insulating member and active material between said members, said active material being provided with spaced surface sections engaging said conductive member and with passageways intermediate said surface sections for facilitating the circulation of electrolyte through the active material, and means securing said members together whereby the active material is maintained under pressure with the said spaced surface sections thereof in close, intimate contact with said conductive member, substantially as described.

5. In a storage battery cell, a pile comprising a plurality of alternately disposed positive and negative elements and insulating members respectively disposed between the adjacent elements, said elements each comprising a conductive sheet and active material respectively disposed adjacent the opposite surfaces of said sheet, the active material adjacent each surface of said sheet having spaced surface sections in close,

intimate contact with such surface and with passageways intermediate the said surface sections and extending through the pile adjacent such sheet for facilitating the circulation of electrolyte through the active material, substantially as described.

6. In a storage battery cell, a plurality of alternately disposed positive and negative elements, and insulating sheets respectively disposed between the adjacent elements, each of said elements comprising a conductive sheet and active material having spaced surface sections engaging said sheet and passageways intermediate said surface sections for facilitating the circulation of electrolyte through the active material, the corresponding passageways in the active material of all said elements being in alignment, substantially as described.

7. In a storage battery cell, a conductive member, an insulating member and a layer of active material between said members, the surface of said layer adjacent the conductive member being grooved to facilitate the circulation of electrolyte through such layer, substantially as described.

8. In a storage battery cell, a conductive member, an insulating member and a layer of active material between said members, the surface of said layer adjacent the conductive member being provided with a series of spaced shallow grooves to facilitate the circulation of electrolyte through such layer, substantially as described.

9. In a storage battery cell, a conductive member, an insulating member and a layer of active material between said members, the surface of said layer adjacent the conductive member being grooved to facilitate the circulation of electrolyte through such layer, and means for securing said members together whereby the active material is maintained under pressure firmly in engagement with said conductive member, substantially as described.

10. In a storage battery cell, a conductive member, an insulating member and a layer of active material between said members, the surface of said layer adjacent the conductive member being provided with a series of spaced grooves to facilitate the circulation of electrolyte through such layer, and means securing said members together whereby the portions of the active material between the grooves in said layer are maintained under pressure firmly in engagement with said conductive member, substantially as described.

11. In a storage battery cell, a plurality of alternately disposed positive and negative elements, each of said elements comprising a conductive sheet and a layer of finely divided active material engaging said sheet, the surfaces of the layers of active material adjacent the conductive sheets being provided with similar series of grooves to facil-

tate the circulation of electrolyte through such layers, and the corresponding grooves in said layers being in alignment, substantially as described.

12. In a storage battery cell, a plurality of alternately disposed positive and negative elements, each of said elements comprising a conductive sheet and layers of finely divided active material respectively engaging the opposite surfaces of said sheet, the surfaces of said layers of active material adjacent said sheet being provided with similar series of grooves to facilitate the circulation of electrolyte through such layers, the corresponding grooves of the two layers of active material engaging said sheet being in alignment, substantially as described.

13. In a storage battery cell, a flat conductive member, an insulating member and a layer of active material between said members, the surface of said layer adjacent the conductive member being provided with a series of spaced parallel grooves to facilitate

the circulation of electrolyte through such layer, and means securing said members together whereby the portions of the active material between the grooves therein are maintained under pressure firmly in engagement with said conductive member, substantially as described.

14. In a storage battery cell, a plurality of alternately disposed positive and negative elements, each of said elements comprising a conductive sheet and layers of finely divided active material maintained under pressure firmly in contact with the opposite surfaces of said sheet respectively, the surface of each of said layers of active material adjacent said sheet being provided with a series of spaced grooves to facilitate the circulation of electrolyte through such layer, substantially as described.

This specification signed this 1st day of February, 1926.

THOS. A. EDISON.
